UNITED STATES PATENT OFFICE.

ULRICH HAGMANN, OF ST. GEORGE, NEW YORK, ASSIGNOR TO THE HOMER LAUGHLIN CHINA COMPANY, OF NEWELL, WEST VIRGINIA, A CORPORATION OF WEST VIRGINIA.

DESIGN FOR A PLATE OR SIMILAR ARTICLE.

Application filed July 8, 1925. Serial No. 14,023. Term of patent 7 years.

To all whom it may concern:

Be it known that I, ULRICH HAGMANN, a citizen of Switzerland, and residing at St. George, Staten Island, borough of Richmond, and State of New York, have invented a certain new, original, and ornamental Design for a Plate or Similar Article, of which the following is a specification, reference being had to the accompanying drawing, forming a part thereof, which is a plan view of a plate showing my new design.

I claim:

The ornamental design for a plate or similar article, substantially as shown:

ULRICH HAGMANN.
